WRIST MOUNTED TENNIS SCORE RECORDER

William R. Trager, Mission Hills, Kans., assignor to Ade Tennis, Inc., Kansas City, Mo.

Filed Feb. 20, 1973, Ser. No. 333,755

Term of patent 3½ years

Int. Cl. D21—01

U.S. Cl. D34—5 MM

Fig. 1.

Fig. 2.

Fig. 3.

Fig. 4.

FIG. 1 is a front perspective view of a wrist mounted tennis scoring recorder, showing my new design;

FIG. 2 is a front plan view, on an enlarged scale, of same;

FIG. 3 is a side elevational view taken from the right-hand side of FIG. 2, the other side being substantially the same in appearance; and

FIG. 4 is an end elevational view, taken from the lower end of FIG. 2, the other end being substantially the same in appearance.

I claim:

The ornamental design for a wrist mounted tennis score recorder, as shown and described.
